UNITED STATES PATENT OFFICE.

ALBERT L. WATSON AND GEORGE L. BARDEN, OF PENN YAN, NEW YORK.

HOOP COILER.

Application filed October 31, 1924. Serial No. 747,003.

This invention aims to provide novel means whereby hoop of the kind used upon a basket, a basket cover, or other basket part, may be coiled. Another object of the invention is to provide novel means for starting and stopping the coiling mechanism. A further object of the invention is to provide novel means for ejecting the coiled hoop.

It is within the province of the disclosure to improve generally and to enhance the utility of devices of that sort to which the invention appertains.

Although a preferred form has been shown, it will be understood that a mechanic, working within the scope of what is claimed, may make changes, without departing from the spirit of the invention.

In the accompanying drawings:—Figure 1 shows in top plan, a device constructed in accordance with the invention, parts being broken away; Figure 2 is a fragmental bottom plan of the top portion of the machine; Figure 3 is a vertical section wherein parts remain in elevation; Figure 4 is a section taken on the line 4—4 of Figure 3; Figure 5 is a fragmental elevation showing portions of the mechanism whereby parts of the device are started and stopped; Figure 6 is a section on the line 6—6 of Figure 3; Figure 7 is a section on the line 7—7 of Figure 1; Figure 8 is a section on the line 8—8 of Figure 1; Figure 9 is an elevation showing a portion of the mechanism whereby the coiling means is started and stopped; Figure 10 is a section on the line 10—10 of Figure 9, parts having been moved, however, from the position shown in Figure 9; Figure 11 is a top plan of the structure shown in Figure 10; Figure 12 is a section showing a portion of the driving mechanism.

In carrying out the invention, there is provided a frame, denoted generally by the numeral 1, the frame comprising a base 2 and a top 3, the top being a composite structure and including an upper member 4, in the form of a plate, and a lower member 5 in the form of a ring. The top 3 and the base 2 are connected by securing elements 6, such as bolts (Figure 4), tubular spacers 7 being mounted on the bolts, the spacers being interposed between the base 2 and the lower ring 5 (Figure 7) of the top 3. Shafts 8 and 9 (Figures 1 and 12) are journaled in the top 3 and are provided with feed rolls 10 located above the upper plate 4

of the top 3. The shaft 8 is supplied with a driving means 11, of any desired sort.

Inner shafts 12 are mounted to rotate in the upper plate 4 of the top 3 and in the lower ring 5 of the top. The shafts 12 preferably are disposed in a circle, and shafts 14, alternating with the shafts 12, are journaled in the parts 4 and 5 of the top 3. The shafts 12 carry pinions 15 (Figure 3) disposed between the parts 4 and 5 of the top 3 of the frame. A shaft 21 (Fig. 8) is journaled in the parts 4 and 5 and is disposed between a pair of the shafts 12, as indicated in Figure 1. The shafts 14 (and a shaft 21 hereinafter mentioned) carry gear wheels 16 meshing (Figure 6) with the pinions 15 on the shafts 12. Outer shafts 17 are journaled in the parts 4 and 5 of the top 3, in radial alignment with the shafts 12. Pinions 18 (Figure 3) are mounted on the shafts 17 and are located between the members 4 and 5 of the top 3. The pinions 18 on the outer shafts 17 mesh with the pinions 15 on the shafts 12, as shown in Figure 1. Feed rolls 19 are mounted on the shafts 12 and cooperate with feed rolls 20 on the shafts 17.

Passing to Figure 4, it will be observed that the shaft 21 carries a beveled pinion 22 meshing with a beveled gear 23 on a horizontal shaft 24 journaled for rotation in bearings 25 on the base 2. A pulley 26 is rotatably mounted on the shaft 24, but may be coupled to the shaft by a mechanism now to be described. The pulley 26 has a hub 27 equipped with an end ratchet 28. A rotatable member 29 is secured to the shaft 24. A pawl 30 (Figure 10) slides in the rotatable member 29 in a direction parallel to the shaft 24, the pawl being advanced by a spring 35 housed within the member 29. The pawl 30 has a beveled shoulder 31 (Figure 11). A lever 32 (Figure 9) is provided, and has a beveled end 33 (Figure 4). The lever 32 is fulcrumed at 34, intermediate its ends, on the base 2. The lever 32 cooperates at one end with a cam 36 attached to a vertical shaft 37 journaled in the base 2 and in the upper plate 4 of the top 3. The shaft carries an arm 38 (Figure 1) located above the upper plate 4 of the top 3. The arm 38 lies in the path of the material 39, as the material is fed into the machine by the rolls 10. The arm 38 has an extension 39 adapted to cooperate with a stop 69 on the plate 4

of the top 3. A torsion spring 40 is connected to the shaft 37 (Figure 9) and is connected to the base 2. The extension 89 on the arm 38 is adapted to cooperate with the stop 69 to limit the rotation of the shaft 37 under the action of the spring 40, when the material 39 is not in the machine.

As shown in Figure 4, bearings 41 are mounted on the base 2, and in the bearings, 10 a shaft 42 is mounted for rotation. A pulley 43 is loose on the outer end of the shaft 42 but is adapted to be coupled thereto. The pulley 43 has a ratchet 44. A rotatable member 45 is secured to the shaft 42, the rotatable member 45 being constructed like the rotatable member 29 shown in Figure 10. A pawl 46 is mounted in the rotatable member 45 and is constructed like the pawl 30 hereinbefore described, the pawl being adapted to 15 cooperate with the beveled end 47 of a crank arm 48 on a shaft 49 mounted for rocking movement in bearings 50 on the base 2. That end of the shaft 49 which is remote from the crank arm 48 carries a crank arm 20 51 (Figure 5) united by a connection 52 with a lever 53 (Figure 3) fulcrumed intermediate its ends on a bracket 54 carried by the lower ring 5 of the top 3. The lever 53 is disposed in the path of a latch 55 pivotally 25 mounted at 56 on the reciprocating hammer 57 of a stapling mechanism or like fastening device.

The mechanism above described provides for the coiling of the material 39 into a hoop. 30 The device includes means for ejecting the hoop after it has been coiled and fastened, and the ejecting means will now be described.

As shown in Figure 3, the shaft 42 is provided with a crank 58 whereunto a pitman 59 (Figure 3) is pivoted, the upper end of the pitman being pivoted at 60 to a tubular slide 61 mounted for vertical reciprocation on a depending guide 62 carried by the upper plate 4 of the top 3. Adjacent to its 40 upper end, the tubular slide 61 is provided with annular flanges 63, between which the inner ends of levers 64 are mounted to rock, the levers being fulcrumed intermediate 45 their ends, as at 65, on hangers 66 carried by the lower ring 5 of the top 3. Ejectors 67, 50 in the form of plungers, are pivotally mounted at 68 on the outer ends of the levers 64 and slide vertically in the constituent parts 55 4 and 5 of the top 3. As Figure 1 will make evident, the plungers or ejectors 67 are located in a circumference disposed between the feed wheels 19 and 20, and are adapted to push upwardly, the finished hoop, after 60 the hoop has been coiled by the action of the feed wheels or rollers 19 and 20.

The material 39 is entered between the feed rolls 10, as shown in Figure 1, and is advanced because the shaft 8 and the corresponding feed roll 10 are rotated by means

of the mechanism shown at 11 in Fig. 5. The material 39 having been advanced, engages the arm 38 (Figure 1) and rocks the shaft 37 (Figures 4 and 5), the spring 40 (Figure 9) being put under torsion. The cam 70 36 on the shaft 37 tilts the lever 32 out of the position of Figure 10 into the position of Figure 9, and the lever 32 is disengaged from the shoulder 31 on the pawl 30 whereupon the pawl is moved to the left (Figure 75 11) and engages with the ratchet 28 on the hub 27 of the pulley 26 (Figure 4), thus coupling the pulley to the shaft 24, since the rotatable member 29 (Figure 10) which carries the pawl 30, is secured to the shaft 24. The shaft 24 now derives rotation from the pulley 26, and the beveled gears 23—22 (Figure 4) rotate the shaft 21 (Figures 1, 3 and 8), the shafts 12 being rotated by way of the pinions 15 on the said shafts, and the 80 corresponding pinion on the shaft 21, the interposed gear wheels 16 exercising their obvious function. The pinions 15 rotate the shafts 17 (Figure 1) by way of the pinions 18 (Figures 1 and 3), the shafts 12 rotating the feed wheels 19, and the shafts 17 rotating the feed wheels 20. The material 39 is drawn around in the form of a hoop by the feed rolls 19 and 20. When the material, having been formed into a hoop, no longer 85 engages the arm 38 on the shaft 37, the spring 40 imparts reverse rotation to the shaft 37 until the extension 89 of the arm 90 38 engages the stop 69 and disposes the arm 38 in the dotted line position of Figure 1, in the path of the next strip of material which is advanced by the feed wheels 10. 100

When the shaft 37 is reversely rotated by the spring 40, as aforesaid, the cam 36 permits the left hand end of the lever 32 (Figure 9) to move downwardly until the beveled end 33 of the lever is in the path of the beveled shoulder 31 on the pawl 30. When the member 29 is rotated, the beveled end 33 of the lever coats with the shoulder 31 on the pawl 30 and retracts the pawl into the position of Figure 10, out of engagement with the ratchet 28 on the pulley 26, the pulley being uncoupled from the shaft 24, and the shaft and the feed rolls 19 and 20 coming to rest, the hoop remaining stationary. The stapling hammer 57 advances to the right in Figure 3 and fastens the ends of the hoop, and as the hammer advances, the latch 55 rides over the upper end of the lever 53. 115 When, however, the hammer 57 moves to the left in Figure 3, the latch 55 first tilts the lever 53 and then passes clear of it, into the position shown in Figures 3 and 1. When the lever 53 is tilted, the connection 52 rocks the shaft 49 by way of the arm 51 (Figure 5). The arm 48 (Figure 4) on the shaft 49 swings clear of the pawl 46 and the pawl 46, being spring-actuated, like the pawl 30, advances into engagement with the ratchet 44. 120 125 130

- on the pulley 43, thus coupling the pulley to the shaft 42. The shaft 42 then is rotated by the pulley 43, and the crank 58 on the shaft 42, together with the pitman 59, 5 raises and lowers the slide 61 (Figure 3), the levers 64 being tilted, and the plungers 67 being raised when the slide moves downwardly, the plungers ejecting the finished hoop from between the feed rolls 19 and 20.
- 10 When the stapling hammer 57 has carried the latch 55 far enough to the left to clear the lever 53, the shaft 49 is set free for rocking movement, and the arm 48 swings downwardly far enough so that its beveled end 47 is in the path of the shoulder on the latch or pawl 46, the latch or pawl being retracted, and being moved out of engagement with the ratchet 44 on the pulley 43, the pulley being uncoupled from the shaft 42, and the 20 shaft 42 coming to rest after the shaft has made one revolution and after the ejecting mechanism has exercised its office.

What is claimed is:—

1. In a machine for coiling material into a hoop, a plurality of inner rotary members supported for individual axial rotation, and located in an arc, and so positioned as to engage the inner surface of the material to be coiled, and a plurality of outer rotary members supported for individual axial rotation, and located in an arc, and so positioned as to engage the outer surface of the material to be coiled, the inner and outer members coaxing to move the material to be coiled, in an arc, means for rotating the inner members and the outer members about their several individual axes, and hoop ejectors operating in the arc in which the material is coiled, and in a direction substantially parallel to the axes of rotation of said inner and outer members, and mechanism for actuating the ejectors together.
2. In a device for coiling material into a hoop, a coiling means, mechanism operated by the material as it is introduced into the machine for starting the coiling means, and released by the material after it has been coiled, to stop the coiling means, means for fastening the hoop after it has been coiled, an ejector for the coiled hoop, and mechanism operated by the fastening means for starting and stopping the ejector. 45
3. In a machine for coiling material into a hoop, a coiling means, mechanism for ejecting the hoop from the coiling means, operating means for the ejecting mechanism and comprising driving and driven parts, means for fastening the hoop after it has been coiled and comprising a movable member, and mechanism for coupling and uncoupling said driving and driven parts, the coupling mechanism including an element located in the path of the movable member of the fastening means and cooperating therewith to effect an uncoupling after the hoop has been 50 fastened and as said member is retracted.
4. In a machine for coiling material into a hoop, a coiling means, operating mechanism, for the coiling means and comprising driving and driven parts, means for coupling 70 and uncoupling said driving and driven parts, one member of the coupling means being so positioned as to be actuated by the material to effect a coupling when the material enters the machine, and mechanism for actuating the coupling means to effect an uncoupling after the material has been coiled and has changed its position with respect to said member of the coupling means. 75

In testimony that we claim the foregoing 80 as our own, we have hereto affixed our signatures.

ALBERT L. WATSON.
GEORGE L. BARDEN.
